ELECTRIC RELAY

Andreas Marius Haslev, Randers, Denmark

Application November 25, 1933, Serial No. 699,778
Renewed March 23, 1937. In Germany July
13, 1933

3 Claims. (Cl. 200—87)

The present invention relates to improvements in electro-magnetic relays of great sensitivity and perfect reliability even after many years of operation. The relay according to the invention is essentially characterized by an armature of magnetic material freely movable inside a container of glass or other insulating material, the container being liberated from oxygen or evacuated and the said armature being provided with a protruding member, which is dipped into mercury in a reservoir formed in the wall of the container to provide a permanent connection.

The invention is schematically represented in the accompanying drawing, where Fig. 1 shows one manner of construction of a relay in accordance with the invention, Fig. 2 a similar relay which may be employed for controlling two separate circuits, and Fig. 3 a modified form of construction of the relay.

The relay shown in Fig. 1 comprises a two-pole electromagnet 1, the pole surfaces 2 of which are recessed into the wall of a suitably formed and arranged container 3 of glass or any other insulating material, which container may be completely liberated from oxygen or wholly or partly evacuated.

The bottom wall of the container 3 is recessed as shown thereby forming a reservoir 4 that serves to hold a quantity of mercury 5, which by means of a platinum wire or the like is connected with one of the leads 6a. Within the container there is a freely movable armature 7 which is provided with a protruding member 8 that is positioned in such a manner and of such a length that it dips into the mercury 5 and maintains this connection during any operation to which the armature may be influenced. Another lead 6b is connected with a contact 9 arranged inside the container 3 in the wall opposite to that in which the reservoir 4 is formed and at the opposite end of the container. When excited the electromagnet will attract the armature 7, which is raised to contact with the contact 9 thereby closing a circuit through the lead 6a, the mercury 5, the armature 7, the contact 9 and the lead 6b. One contact 9 will suffice, but by applying for instance two contacts, one at each end of the armature, a better contact is secured when the armature is raised by the electromagnet.

The relay illustrated in Fig. 2 is applicable to the controlling of two separate circuits. For this purpose another contact 10 is arranged in the bottom wall of the container 3 and connected with a lead 6c. It is assumed that otherwise the relay is of the type described in connection with

the preceding figure. The mercury in the reservoir 4 is connected with two leads 6a and 6d, one for each circuit in question. Normally the relay closes the one circuit through the lead 6d, the mercury 5, the armature 7, the contact 10 and the lead 6c, but when the electromagnet is excited the armature 7 will be raised interrupting the circuit mentioned and close the other circuit through the lead 6a, the mercury 5, the armature 7, the contact 9 and the lead 6b.

The relay shown in Fig. 3 is of substantially the same design as the construction shown in Fig. 1, but in addition to the mercury reservoir 4 a corresponding reservoir 11 is recessed in the opposite wall of the container, and the protruding member 8 is extended through the armature, thus forming another protruding member 12 opposite the reservoir 11. In the position illustrated the action of the relay is exactly the same as that of the construction shown in Fig. 1, but upon reversing the container 180° around its longitudinal axis so that the contact 9 and the reservoir 11 are turned downwards, the mercury 5 will flow into the reservoir 11, and a circuit is closed through a lead 6e in this reservoir, the mercury 5, the armature 7, the contact 9 and the lead 6b. The electromagnet is in this manner of construction not recessed into the wall of the container 3, but maintains its position above the container and when excited interrupts or closes the one or the other of the circuits according to the position of the container.

I claim:

1. In an evacuated container of insulated material of an electromagnetic relay, the combination of a loose and freely movable armature made of a straight piece of flat soft iron, a pin disposed near one end of the armature and protruding downwardly therefrom, a cup-shaped reservoir in the lower portion of the container wall for mercury, said reservoir positioned and said pin shaped in such a manner as to allow the immersion of the latter in the mercury during any movement of the armature in operation, and a contact in the container wall for closing a circuit through the armature when it is actuated.

2. In an evacuated container of insulating material of an electromagnetic relay, the combination of a loose and freely movable armature made of a straight piece of flat soft iron, a pin disposed near one end of the armature and protruding downwardly therefrom, a cup-shaped reservoir in the lower portion of the container wall for mercury, said reservoir positioned and the said pin shaped in such a manner as to allow

immersion of the latter in the mercury during any movement of the armature in operation, and two contacts in the container wall, one of which contacts serves the purpose of closing a circuit 5 through the armature when inactive, and the other contact the purpose of closing another circuit through the armature when actuated, the former circuit being simultaneously interrupted.

3. In an evacuated container rotatable on its 10 longitudinal axis of insulation material of an electromagnetic relay, the combination of a loose and freely movable armature made of a straight piece of flat soft iron, a pin inserted through the armature near one end thereof, the ends of the

pin protruding in opposite directions, cup-shaped reservoirs for mercury in the wall of the container and disposed opposite each other and each in relation to the one of the protruding pin ends to allow the immersion of the corresponding pin end in the mercury gathered in the reservoir that at the moment is lowermost during any movement of the armature in operation, and a contact for closing a circuit through the armature when actuated in one position of the container, whereas in the opposite position resulting from rotation of the container another circuit is closed through the armature when inactive. 5 10
